SAFETY RAZOR

John D. Garretson, Oakland, Calif., assignor to
 Godfrey Dalkowitz, Brooklyn, N. Y., and John
 D. Garretson, Oakland, Calif., trustees

Application October 25, 1933, Serial No. 695,133

19 Claims. (Cl. 30—61)

This invention relates particularly to a safety razor consisting of a guard member supported on a handle, a two part blade backing member, and a thin flexible blade to be clamped between the guard and backing members, to hold the cutting edges of the blade overlying a slot in each of the opposite edges of the guard, the two part blade backing member being hingedly supported on the guard to assume a folded position at times, to permit the installation or removal of the blade from the guard member.

An object of the invention is to provide a safety razor on which the blade may be placed or removed without the necessity of disassembling or taking apart the safety razor, the said razor having a blade backing member thereon which assumes an extended position to clamp the blade onto the guard member, and assumes a folded position to permit the blade to pass thereover when being placed on or removed from the guard member.

A still further object is to provide a safety razor wherein the blade backing member is foldable to pass thru an elongated slot in the blade, said blade being of a peculiar slotted type for co-operation with a safety razor of the character specified.

Other objects and advantages are to provide a safety razor that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

In the accompanying drawing:

Fig. 1 represents a vertical cross section thru a razor constructed in accordance with my invention, and showing the blade backing member in the fully elevated or folded position.

Fig. 2 is a cross section similar to Fig. 1, showing the blade backing member intermediate the folded and extended positions.

Fig. 3 is a vertical cross section similar to Fig. 1,

and showing the blade backing member in the extended and operative position.

Fig. 4 is a plan view of Fig. 1, a portion of the blade being broken away to show the slots in the guard member.

Fig. 5 is a plan view of Fig. 3.

Fig. 6 is a cross section taken thru Fig. 5 on the line 6—6 to show the hinged connection of the two part blade backing on the guard member.

Fig. 7 is a reduced size longitudinal cross section taken thru Fig. 1 on the line 7—7.

In the drawing, the numeral 1 indicates a guard member provided with a slot 2 along each of its opposite longitudinal edges. The upper center surface of the guard 1 is flattened as at 3, and the sides of the guard adjacent the flattened portion, are curved downwardly and outwardly as at 4, at a proper angle for contacting the razor with the face during the shaving operation.

The guard member is mounted on a hollow handle 5 which is secured to the center of the guard on the underside thereof. A stem 6 is slidably confined in the tubular handle 5. The lower end of the handle 5 is shouldered and threaded to receive a head 7, said head being rotatable around the lower end of the handle 5. The lower end of the stem 6 is threaded as at 8, to engage an internally threaded portion 9 on the head 7, whereby rotation of the head 7 causes the stem 6 to move axially in the handle 5, thru and by reason of the co-engaging threaded portions on the stem 6 and head 7.

The upper end of the handle 5 where it joins the underside of the guard member 1, is enlarged in diameter as at 10 to provide a cavity 11 of substantial area around the stem 6.

A bar 12 is provided on the longitudinal center line of the guard member 1, the upper portion of said bar 12 projecting a substantial distance above the upper flat surface 3 of the guard member, and the length of said bar 12 being the same as the length of the guard member.

A blade backing member consisting of a pair of like halves 13, has each of its opposite ends pivotally attached to opposite ends of the bar 12, there being aligned pins 14 in each of the opposite ends of the bar 12 to form journals on which the respective halves of the blade backing member may swing from the folded position shown in Fig. 1, into the extended position shown in Fig. 3, and

vice versa. The opposite longitudinal edges 15 of the blade backing members form surfaces to engage the opposite sides of the blade, adjacent the cutting edges thereof. On the underside of each 5 of the halves of the blade backing member is provided a depending stud 16, which stud is provided with a longitudinally disposed cam slot 17 therein. The stud 16 is positioned substantially midway between the ends of the halves of the blade backing 10 member on which it is mounted.

The upper end of the stem 6 is provided with an enlarged shoulder 18 thereon, on opposite sides of which a pair of arms 20 project in parallel with the length of the stem 6. The arms 20 are spaced 15 apart a distance corresponding to the width of the bar 12. Each of the arms 20 extend thru openings provided in the flattened portion of the guard member 1 on opposite sides of the bar 12 and at a point midway between the opposite ends 20 of the guard member. The upper end of each arm 20 terminates in a slotted clevis 21.

The stud 16 on each of the halves of the blade 25 backing member, is adapted to be confined within the slot of each clevis 21, there being a pin 22 fixed in each clevis which extends thru the slot 17 in the stud 16. The stem 6 is limited in its reciprocal movements by the engagement of the shoulder 18 with the underside of the guard 1 when the stem is moved upwardly, and the engagement of said shoulder 18 with the base of the 30 socket 10 in the handle 5, when the stem is moved downwardly.

When the head 7 on the handle 5 is rotated 35 from the position shown in Fig. 1, the stem 6 is retracted axially in the handle to lower the blade backing members from the folded position shown in Fig. 1 into the partially extended position shown in Fig. 2, and thence into the fully extended position shown in Fig. 3. The blade backing 40 member is held in the extended position shown in Fig. 3, by turning the head 7 on the handle to exert a downward pull on the center portion of the opposite halves of said blade backing member, thus preventing the same from swinging into the 45 folded position.

When the blade backing member is in the elevated position shown in Fig. 1, the arms 20 on the stem 6, thru engagement with the slotted portions 50 on the opposite halves of the blade backing member, cause said halves of the blade backing member to remain in the folded position. By reason of the fact that the opposite halves of the blade 55 backing member are fixedly pivoted to the bar 12 at their opposite ends, said members always swing about the center of said pivotal connection. The pin and slot connection between the halves of the blade backing member and the stem merely effects raising and lowering movement of the halves of the blade backing member into and from the 60 folded and extended positions.

Whenever the blade backing member is lowered 65 from the elevated position shown in Fig. 1, into the positions shown in Figs. 2 and 3, or whenever the blade backing member is moved in the reverse direction from the extended and into a bowed position, the action of the clevis pins 22 engaging the sides of the slots 17 in the stud 16, cause the opposite halves of the blade backing member to move in the desired direction. The 70 length of movement of the stem 6 permits the blade backing member to be moved away from the guard 1 into a position of substantial registry with the bar 12, the thickness of the two halves of the blade backing member substantially corresponding to the thickness or width of the bar 12. 75

A blade 25 to be mounted upon the razor above described, is of the thin, flexible type, having cutting edges on each of the opposite longer sides thereof, and is provided with a central longitudinal aperture 26, the central portion of which 5 is enlarged at 27. The length of the slot 26 is greater than the length of the bar 12, and likewise is greater than the length of the blade backing member, whereby when the blade is dropped over the backing member, in the collapsed position shown in Fig. 1, and onto the guard member, the blade cannot move lengthwise in either direction. Sidewise movement of the blade is prevented by engagement of the longer side edges of the slot in the blade with the side faces of the bar 15 12 or stem arms 20. The width of the slot 26 and enlargement 27, is slightly more than the overall thickness of the opposite halves of the blade backing member when in the folded or collapsed position, shown in Fig. 1, and the bar 20 12, whereby said blade will pass freely over the folded halves and the bar when either placing the blade on or removing it from the razor. The contour of the slot 26 and its enlargement 27, correspond to the outline or boundary of the 25 backing member when in the folded position, and of the bar 12.

When the blade is to be placed on or removed from the razor, the backing member is first brought into the position shown in Fig. 1, the opposite ends of the blade are grasped between the fingers, and the central opening of the blade is moved relative to the folded halves of the blade backing member and the bar 12, until the slotted portion of the blade engages or disengages the opposite sides and ends of the projecting bar 12 on the guard member. When the blade is properly positioned on the guard, opposite halves of the blade clamping member clamp the opposite cutting edges of the blade in shaving position, along the opposite sides of the guard member as shown in Fig. 3.

Having thus described this invention, what I claim and desire to secure by Letters Patent is:

1. A safety razor, comprising a guard member 45 provided with a blade positioning member on one side thereof and a tubular handle on the other side; a blade backing member formed of complementary halves, each of which are hingedly mounted on the blade positioning member; a stem to move axially in said handle and having the upper end thereof slidably pivoted to the opposite halves of the backing member, whereby said backing member is movable from an extended position in contact with the guard into a collapsed position above the guard, and vice versa; a blade to be clamped between the guard and blade backing member and having a central longitudinal slot fitting over the blade positioning member and being of a length and width exceeding that of the blade backing member when in the collapsed position; and coacting means on the stem and handle for relatively moving said blade backing member into and from blade clamping position on the guard. 55

2. A safety razor, comprising a guard member provided with a blade positioning member; a blade backing member consisting of complementary halves hingedly connected to the blade positioning member; means slidably at right angles to said guard member, the halves of said blade backing member being slidably hinged on said slidable means to cause each of the longitudinal edges thereof to substantially coincide with the longitudinal edges of said guard mem- 75

ber when in the extended position and to fold into a collapsed position parallel to the blade positioning member when in the raised position; a blade adapted to be clamped between said guard and blade backing member having a central longitudinal slot, the ends of which fit said blade positioning member, and being of a length exceeding that of said blade backing member, the width of said slot exceeding the width of the halves of the blade backing member when in the folded position, said slot permitting the blade to be moved over the folded halves of the blade backing member and said slidable means when the latter is raised away from the guard; and means for relatively moving the said blade backing member into clamping position with the guard.

3. A safety razor, comprising a guard member provided with a blade positioning member; a blade backing member consisting of complementary halves hingedly connected to the blade positioning member; means slidable at right angles to said guard member, the halves of said blade backing member being slidably hinged on said slidable means to cause each of the longitudinal edges thereof to substantially coincide with the longitudinal edges of said guard member when in the extended position and to fold into a collapsed position on opposite sides of the slidable means when in the raised position and to hold the opposite halves in non-swinging folded position on opposite sides of the slidable member when the blade backing member is in the raised position; a blade adapted to be clamped between said guard and blade backing member having a central longitudinal slot, the ends of which fit said blade positioning member and being of a length exceeding that of said blade backing member, the width of said slot exceeding the width of the halves of the blade backing member when in the folded position, said slot permitting the blade to be moved over the folded halves of the blade backing member and said slidable means when the latter is raised away from the guard; and means for relatively moving the said blade backing member into clamping position with the guard.

4. A safety razor, including a guard member; a blade; and a cap to engage the blade with the guard member, said cap being divided on its central longitudinal axis into two halves each of which is hingedly connected to the guard member along the longitudinal center line thereof, whereby the cap may be elevated relative to the blade and the two halves of the cap will fold up into a position at right angles to the plane of the guard.

5. A safety razor, including a guard member; a blade; and a cap to engage the blade with the guard member, said cap being divided on its central longitudinal axis into two halves each of which is hingedly connected to the guard member along the longitudinal center line thereof, whereby the cap may be elevated relative to the blade and the two halves of the cap will fold up into a position at right angles to the plane of the guard; and means to hold the two halves of the cap in a non-swinging position when the cap is in the folded elevated position.

6. A safety razor, including a guard member; a blade; and a cap to engage the blade with the guard member, said cap being divided into two separate halves, each of which is hingedly connected to the upper side of the guard member along a center line thereof, whereby the cap may be elevated relative to the blade and the two

halves of the cap will fold up into a position at right angles to the plane of the guard.

7. A safety razor, including a guard member having a longitudinally disposed bar projected along the upper face thereof; a blade positioned by said bar on the guard member; and a cap to engage the blade with the guard member, said cap being divided on its central longitudinal axis into two halves each of which is hingedly connected at the opposite ends thereof to the bar on the guard member, whereby the two halves of the cap will fold up into a position parallel to the longer side walls of the bar on the guard member.

8. A safety razor, including a guard member having a longitudinally disposed bar projected along the upper face thereof; a blade positioned by said bar on the guard member; a cap to engage the blade with the guard member, said cap being divided on its central longitudinal axis into two halves each of which is hingedly connected at the opposite ends thereof to the bar on the guard member, whereby the two halves of the cap will fold up into a position parallel to the longer side walls of the bar on the guard member; and means engaging the opposite halves of the cap to move the same into engagement with the blade on the guard member at times and at other times to move the halves of the cap into the folded position.

9. A safety razor, including a guard member; a blade; a cap to engage the blade with the guard member, said cap being divided into two separate halves, each of which is hingedly connected to the upper side of the guard member along a center line thereof, whereby the cap may be elevated relative to the blade and the two halves of the cap will fold up into a position at right angles to the plane of the guard; and means engaging the opposite halves of the cap to move the same into engagement with the blade on the guard member at times and at other times to move the halves of the cap into the folded position.

10. In a safety razor, a guard with slots adjacent the outer longitudinal edges thereof, and with a blade positioning bar across a center line thereof; a tubular handle having one end attached to the guard; two blade flexing members hingedly attached on opposite sides of the blade positioning bar, said members being raisable into parallel positions substantially at right angles to the plane of the guard for blade installation or removal, and movable to positions substantially parallel to the plane of the guard for bringing a flexible blade into flexed contact with the guard with the outer edges of blade parallel to longitudinal edges of guard; slidable means within the tubular handle connected with the blade flexing members for raising and lowering the same into blade placement and blade flexing positions; and a flexible blade having opposite cutting edges, and having a central aperture of dimensions adapted to pass over the blade flexing members, when in the raised positions, and also over the blade positioning bar, the said aperture being enlarged at the middle thereof to fit over the means for the raising and the lowering of the blade flexing members.

11. A razor comprising a blade seat and guard and means for clamping a blade thereon, said means comprising clamping sections each hinged at one end to swing about an axis intermediate the opposed ends of the blade seat, the two being so related as to swing oppositely from a position of adjacent parallelism for blade releasing pur-

poses to a position in end to end relation for blade clamping purposes.

12. In combination, a razor comprising a blade seat having blade guards along opposite edges, 5 and a cover for clamping the blade, said cover comprising two members mounted for relative movement from an end to end relation to a position of substantial parallelism, and a blade having a slot of a length and width at least equal to 10 the horizontal projection of both said cover members when in such position of substantial parallelism so that with the clamping members in such position of substantial parallelism, the aforementioned slotted blade can be seated and 15 unseated merely by lifting it over said clamping members.

13. A safety razor, comprising a guard member provided with blade positioning studs on one side thereof and a tubular handle on the other side; 20 a blade backing member hinged on its longitudinal center line to form complementary halves; a stem to move axially in said handle and having the upper end thereof pivotally connected to the opposite halves of the backing member, whereby 25 said backing member is movable from an extended position in contact with the guard into a collapsed position above the guard, and vice versa; a blade to be clamped between the guard and blade backing member and having a central 30 longitudinal slot fitting over the blade positioning studs and being of a length and width exceeding that of the blade backing member when in the collapsed position; and coacting means on the stem and handle for relatively moving said blade backing member into and from blade clamping position on the guard.

14. A safety razor, comprising a guard member provided with blade positioning studs on one side thereof and a tubular handle on the other side; a blade backing member hinged on its longitudinal center line to form complementary halves; a stem to move axially in said handle and having the upper end thereof pivotally connected to the opposite halves of the backing member, whereby 45 said backing member is movable from an extended position in contact with the guard into a collapsed position above the guard, and vice versa; means pivotally connected to each of the opposite halves of the blade backing member to hold said halves in collapsed position when the blade backing member is elevated above the guard; a blade to be clamped between the guard and blade backing member and having a central 50 longitudinal slot fitting over the blade positioning studs and being of a length and width exceeding that of the blade backing member when in the collapsed position; and coacting means on the stem and handle for relatively moving said blade backing member into and from blade clamping 55 position on the guard.

15. A safety razor comprising a guard member provided with blade positioning studs; a blade backing member consisting of complementary halves hingedly connected along one side thereof; means 60 slidably at right angles to said guard member, the halves of said blade backing member being hingedly mounted on said slidable means to cause each of the longitudinal edges thereof to substantially coincide with the longitudinal edges of said guard member when in the extended position and to fold into a collapsed 65 position on opposite sides of the slidable means when in the raised position; a blade adapted to be clamped between said guard and blade backing member having a central longitudinal slot, the

ends of which fit said blade positioning studs, and being of a length exceeding that of said blade backing member, the width of said slot exceeding the width of the halves of the blade backing member when in the folded position, said slot 5 permitting the blade to be moved over the folded halves of the blade backing member and said slid- 10 able means when the latter is raised away from the guard; and means for relatively moving the said blade backing member into clamping posi- 15 tion with the guard.

16. A safety razor comprising a guard member provided with blade positioning studs; a blade backing member consisting of complementary halves hingedly connected along one side thereof; 15 means slidable at right angles to said guard member the halves of said blade backing member being hingedly mounted on said slidable means to cause each of the longitudinal edges thereof to substantially coincide with the longitudinal edges 20 of said guard member when in the extended position and to fold into a collapsed position on opposite sides of the slidable means when in the raised position; means pivotally connected to each of the opposite halves of the blade backing mem- 25 ber to hold the opposite halves in non-swinging folded position on opposite sides of the slidable member when the blade backing member is in the raised position; a blade adapted to be clamped between said guard and blade backing member 30 having a central longitudinal slot the ends of which fit said blade positioning studs and being of a length exceeding that of said blade back- 35 ing member, the width of said slot exceeding the width of the halves of the blade backing member when in the folded position, said slot permitting the blade to be moved over the folded halves of the blade backing member and said slidable means when the latter is raised away from the guard; and means for relatively moving the said 40 blade backing member into clamping position with the guard.

17. A safety razor including in combination a head; a handle for said head, said head comprising a guard element and a cap element, said 45 cap element being divided into foldable comple- 50 mentary halves; means mounted in said handle and operatively related to the guard element and cap element for moving said cap element toward or from the guard element; a blade to be posi- 55 tioned between said guard element and said cap element and formed with an opening for the pas- 60 sage of said cap element; and means whereby said cap element may be brought into a position ex- 65 tending at an angle to the guard element during its passage through the blade opening.

18. A razor including in combination a head, a handle for said head, said head comprising a guard element, a clamping plate element, said 60 clamping plate element and guard element being 65 hingedly connected, means mounted on one of said elements and operatively related to the other element for moving one of said elements toward or from the other, whereby the movable element 70 may be brought at one time to a position sub- 75 stantially parallel with the other element and at another time brought to an angle to the other element during its passage through the blade opening, and a blade to be positioned between said elements and formed with an opening for the 70 passage of one of the same.

19. A razor including, in combination a head, a handle for said head, said head comprising a guard element, a clamping plate element, said 75

clamping plate element and guard element being hingedly connected; means within the handle and guard element operatively related to the cap element for maintaining said cap element approximately parallel with said guard element at times, and for moving said cap element away from said guard element to a position approximating a 90

degree angle thereto at other times; and a blade to be positioned between said elements and formed with an opening for the passage of the cap element when said cap element is in the position approximating a 90 degree angle to the 5 said guard element.

JOHN D. GARRETSON.
